DESIGN FOR A TOY WHISTLING WINDMILL

Steve Kalisz, Chicago, Ill.

Application May 21, 1945, Serial No. 119,660

Term of patent 14 years

(Cl. D3—15)

To all whom it may concern:

Be it known that I, Steve Kalisz, a citizen of the United States, residing at Chicago, in the county of Cook and State of Illinois, whose post office address is 4616 South Albany Avenue, Chicago, Illinois, have invented a new, original, and ornamental Design for a Toy Whistling Windmill, of which the following is a specification, reference being had to the accompanying drawing, forming a part thereof.

In the drawing:

Fig. 1 is a front elevational view of my new design for a toy whistling windmill;

Fig. 2 is a side view thereof; and

I claim:

The ornamental design for a toy whistling windmill, as shown.

STEVE KALISZ.
